UNITED STATES PATENT OFFICE.

JAMES G. BARNETT, OF NEWARK, NEW JERSEY.

HOLDER FOR RAZOR-BLADES.

No. 836,079.

Specification of Letters Patent.

Patented Nov. 20, 1906.

Application filed April 18, 1906. Serial No. 312,335.

To all whom it may concern:

Be it known that I, JAMES G. BARNETT, a citizen of the United States, residing at Newark, in the county of Essex and State of New Jersey, have invented certain new and useful Improvements in Holders for Razor-Blades; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 This invention refers to a device for holding the blade of a safety-razor for sharpening purposes, in which the blade can be quickly inserted and quickly withdrawn and that is extremely simple to operate.

20 Previous devices of this kind have consisted of a tubular sleeve in which the back of the blade was slid, and when the blade was honed the circular sleeve raised the back end of the blade so far away from the stone that 25 it was impossible to hold the razor-blade at the proper angle to the stone to secure a good edge. The back of the blade could not engage the stone.

My device holds the blade securely, and 30 when the blade is sharpened on a stone none of the holder comes in contact with the stone in the sharpening process.

The invention is illustrated in the accompanying drawings, in which—

35 Figure 1 is a perspective view of my improved device with a blade inserted. Fig. 2 is a side view of the holding end of the device with the blade removed. Fig. 3 is a top view of the same, and Fig. 4 is an end view 40 with the blade in place.

I construct my device preferably with a handle 10, and on the end of the handle is secured a shank 11, with a short bar 12 normally in line therewith and pivoted at 13. 45 The shank 11 and the bar 12 each have the finger 14 projecting therefrom, these fingers being pointed, as at 15. On each side of each finger is a lip 16, which are so disposed that they will engage on both sides of both ends

to the concave portion 17 of the blade 18, the 50 back of the blade engaging the shank 11 and the bar 12.

To remove or insert a blade, the bar 12 is pulled down, as in Fig. 2, and when it is replaced it securely grips the razor-blade. To 55 hold the blade secured, a bar 19 is pivoted on the back to the shank 11 by means of the pivotal pin 20; but any equivalent means might be employed to lock the bar 12 in line with the shank 11.

In Fig. 4 I show a dotted line that represents where the points of the contact would come when the blade is honed or sharpened, and this figure illustrates that the edge and the back of the blade are the only points in 65 the device that are engaged as the fingers of the holder rest in the concavity of the blade.

Having thus described my invention, what I claim is—

1. A device of the kind described, comprising a shank having a finger projecting therefrom, a bar hinged on the end of the shank and having a finger projecting therefrom, means for locking the shank and the bar in line, and lips on the opposed faces of 75 the fingers to engage the sides of a blade.

2. A device of the kind described, comprising a shank having a finger projecting therefrom, a bar hinged to the end of the shank and having a finger projecting therefrom, lips on the opposed faces of the fingers to engage the sides of a blade, and a bar pivoted intermediate of its ends on the back of the shank.

3. A device of the kind described, comprising a shank having a finger projecting therefrom, a bar hinged on the end of the shank and having a finger projecting therefrom, means for locking the shank and the bar in line, and means on the opposed faces 90 of the fingers to engage a razor-blade.

In testimony that I claim the foregoing I have hereunto set my hand this 13th day of April, 1906.

JAMES G. BARNETT.
